Patented July 1, 1975

235,660

COMBINED PORTABLE 8-TRACK TAPE PLAYER AND AM/FM TUNER

Richard Culbertson, Manlius, and Cornelius W. Cristie,
Jr., Fulton, N.Y., assignors to General Electric Com-
pany

Filed July 11, 1974, Ser. No. 487,568

Term of patent 14 years

Int. Cl. D14—01, 03

U.S. Cl. D26—14 B

FIG.2

Des. 235,660

PAGE 2

FIG.6

FIG. 1 is a front elevation view of a combined portable 8-track tape player and AM/FM tuner, showing our new design;

FIG. 2 is a top plan view of the player;

FIG. 3 is a left side elevation view of the player;

FIG. 4 is a right side elevation view of the player;

FIG. 5 is a bottom plan view of the player; and

FIG. 6 is a rear elevation view of the player.

We claim:

The ornamental design for a combined portable 8-track tape player and AM/FM tuner, as shown.
